UNITED STATES PATENT OFFICE.

JOHANN SENN, OF BERNE, SWITZERLAND.

FASTENING DEVICE.

No. 873,271.

Specification of Letters Patent.

Patented Dec. 10, 1907.

Application filed September 16, 1905, Serial No. 278,691.

To all whom it may concern:

Be it known that I, JOHANN SENN, a citizen of Switzerland, residing at Berne, in the canton of Berne, Switzerland, have invented 5 certain new and useful Improvements in Fastening Devices, of which the following is a specification.

My invention relates to fastening devices for lacing shoes and other articles in which 10 laces are used.

The object of my invention is to produce a fastening device which is so constructed that the roller around which the laces are guided, is rotatably held between a cap of thin sheet 15 metal and a base-plate, also of sheet metal, the cap and the base plate being firmly secured together, in such a manner, that no protruding edges or corners are left to catch the dress, the whole presenting a neat appearance, the cap having a perfectly smooth surface.

The cap is provided with convenient holes through which the lacing passes around the roller, the latter being securely held in place. 25 Another plate is provided, which is clamped together with the cap and the base-plate and has a hollow shank, whereby the fastening device can be firmly attached to the upper of a shoe or in the fabric of other articles, in 30 which laces are used.

On the accompanying drawings, illustrating the invention, Figure 1 is a vertical section and Fig. 2 a plan view of one construction of the new fastening device; Figs. 3 and 35 4 are similar views of another construction, and Fig. 5 is a modified form of roller which may be substituted for the form shown in Fig. 3.

Similar reference characters designate similar parts in all the figures.

Referring first to Figs. 1 and 2, the cap *b* consists of a housing made of thin sheet metal, in which a roller consisting in this instance of a small ball *a* is located, which ball 45 is held between the top of the cap *b* and a bearing plate *c*. To prevent the ball from slipping, the plate *c* and the cap *b* are provided with indentations 1 and 2 respectively, in which the ball is securely held. The plate 50 *c* rests on the overturned edges of a hollow shank *e*, which is passed through the material, adapted to receive the fastening device and secured thereto by bending over the lower edge 5. Instead of clamping the edge 55 5 against the material, a flat ring *6* is inter-

posed between the edge 5 and the material, the ring 6 serving in this case as a washer.

As seen from Fig. 1, the upper bent edge of the shank *e*, whereby plate *c* is supported, is held together with the said plate in the overturned lower edge of the cap *b*, the parts being clamped firmly together, as if practically made of one piece, and, as seen from Fig. 1, the ball *a* is held securely between the cap *b* and base-plate *c*, being prevented from displacement by the indentations 1 and 2.

The cap *b* is provided with lateral openings 3 and 4 (Fig. 2), through which the lacing *d* extends, passing inside the cap around the ball *a*, the cap being of such diameter 70 to permit the lacing *d* a sufficient clearance to freely glide around the ball *a*. The whole as seen, presents a neat appearance, being entirely smooth without any corners or projections.

The construction of the fastening device, shown in Figs. 3 and 4, is very similar to that shown in Figs. 1 and 2, except that in this case instead of a ball *a* a roller consisting of a cylinder *a* is provided in the cap, 80 the roller having points at opposite ends, whereby the same is journaled in the top of the cap and the base-plate *c*. For this purpose the cap and the base plate *c* are provided, like in Fig. 1, with corresponding indentations 1 and 2. The surface of the roller *a* may be concave, as indicated in Fig. 5, so as to offer the lacing a better guide.

By providing the roller with points, the friction in the bearings 1 and 2 is considerably reduced.

What I claim as my invention and desire to secure by Letters Patent is:—

1. A fastening device for laces, comprising a flanged attaching shank, a plate superposed thereon, a cap uniting the peripheries of said shank-flange and plate, and a roller rotatably mounted between said cap and plate; the cap having orifices to permit a lace to be passed behind the roller.

2. A fastening device for laces, comprising a flanged attaching shank, a plate superposed on the flange of said shank, a cap uniting said plate and flange throughout their peripheries, and a roller rotatably mounted between said cap and plate; said cap having orifices to permit a lace to be passed behind the roller.

3. A fastening device for laces, comprising a hollow flanged attaching shank, a plate

resting on said flange, a cap having its edges compressed about the edges of the plate and shank-flange to unite the parts, and a roller rotatably mounted in depressions in the cap and plate; said cap having orifices to permit a lace to be passed behind the roller.

4. A fastening device for laces, comprising a recessed plate, a laterally apertured cap having a recessed top, a roller rotatably mounted in said plate and cap, and means for attaching the fastening to an article of apparel; said cap apertures being suitably located to permit a lace to be passed behind the roller.

5. A fastening device for laces, comprising 15 a hollow, flanged attaching shank, a recessed plate resting on said flange, an externally-smooth, recessed cap uniting said plate and shank-flange throughout their peripheries, a roller journaled in the recesses of said cap 20 and plate, and means for securing said shank to an article of apparel.

In testimony whereof I affix my signature in presence of two witnesses.

JOHANN SENN.
